US0D1109881S

(12) **United States Design Patent** (10) Patent No.: **US D1,109,881 S**
(45) Date of Patent: ** Jan. 20, 2026

(54) **SKIN AESTHETIC APPARATUS**

(71) Applicant: **CERAGEM CO., LTD.**,
Chungcheongnam-do (KR)

(72) Inventors: **Junghyun Jo**, Gyeonggi-do (KR);
Jongoh Lee, Gyeonggi-do (KR);
Daesung Kim, Seoul (KR)

(73) Assignee: **CERAGEM CO., LTD.**,
Chungcheongnam-do (KR)

(**) Term: **15 Years**

(21) Appl. No.: **29/949,278**

(22) Filed: **Jun. 26, 2024**

(30) **Foreign Application Priority Data**

Dec. 27, 2023 (KR) 30-2023-0053093
Jun. 12, 2024 (KR) 30-2024-0023022

(51) **LOC (15) Cl.** **28-03**

(52) **U.S. Cl.**

USPC **D24/214**

(58) **Field of Classification Search**

USPC D24/200, 214, 211

CPC A61N 1/327; A61N 1/328; A61N 1/18

See application file for complete search history.

(57) **CLAIM**

The ornamental design for a skin aesthetic apparatus, as shown and described.

DESCRIPTION

FIG. 1 is a perspective view of the skin aesthetic apparatus, showing our new design;

FIG. 2 is a front view of the skin aesthetic apparatus;

FIG. 3 is a rear view of the skin aesthetic apparatus;

FIG. 4 is a left side view of the skin aesthetic apparatus;

FIG. 5 is a right side view of the skin aesthetic apparatus;

FIG. 6 is a top view of the skin aesthetic apparatus; and,

FIG. 7 is a bottom view of the skin aesthetic apparatus.

The broken line showing of skin aesthetic apparatus is included for the purpose of illustrating the article and forms no part of the claimed design.

1 Claim, 7 Drawing Sheets
